US0D1019281S

(12) **United States Design Patent** (10) **Patent No.:** **US D1,019,281 S**
(45) **Date of Patent:** **** Mar. 26, 2024**

(54) **MUG**

(71) Applicant: **MiiR Holdings, LLC**, Seattle, WA (US)

(72) Inventor: **Bryan Pape**, Seattle, WA (US)

(73) Assignee: **MiiR Holdings, LLC**, Seattle, WA (US)

(**) Term: **15 Years**

(21) Appl. No.: **29/740,314**

(22) Filed: **Jul. 2, 2020**

(51) **LOC (14) Cl.** 07-01

(52) **U.S. Cl.**

USPC **D7/536; D7/509**

(58) **Field of Classification Search**

USPC D7/507, 510, 514, 532, 533, 536, 537, D7/538, 543, 608, 622; D9/602; D14/207

CPC A47J 41/0077; A47J 31/02; A47J 31/14; A47G 19/2288; A47G 19/2205; A47G 19/14; A47G 19/16; A47G 19/2227; B65D 81/3876; B65D 85/8061

(57) **CLAIM**

The ornamental design for a mug, as shown and described.

DESCRIPTION

FIG. 1 is a perspective view of a first embodiment of a mug, showing my new design;

FIG. 2 is a rear elevational view thereof;

FIG. 3 is a front elevational view thereof;

FIG. 4 is a left elevational view thereof;

FIG. 5 is a right elevational view thereof;

FIG. 6 is a top plan view thereof;

FIG. 7 is a bottom plan view thereof;

FIG. 8 is a perspective view of a second embodiment of a mug showing my new design;

FIG. 9 is a rear elevational view thereof;

FIG. 10 is a front elevational view thereof;

FIG. 11 is a left elevational view thereof;

FIG. 12 is right elevational view thereof;

FIG. 13 a top plan view thereof; and,

FIG. 14 is a bottom plan view thereof.

The broken lines in FIGS. 1, 2, 6, 7, 8, 10, 13, and 14 are for the sole purpose of showing portions of the mug, and do not form a part of the claimed design.

1 Claim, 8 Drawing Sheets
